UNITED STATES PATENT OFFICE.

EDWIN MARC FRANCOIS GUIGNARD, OF SHANGHAI, CHINA, ASSIGNOR TO UNDER-
WOOD TYPEWRITER COMPANY, OF NEW YORK, N. Y., A CORPORATION OF
DELAWARE.

TYPEWRITING MACHINE.

Application filed October 15, 1918. Serial No. 258,207.

To all whom it may concern:

Be it known that I, EDWIN MARC FRANCOIS GUIGNARD, a citizen of Switzerland, residing in the city of Shanghai, in the Province of 8 Kiangsu and Republic of China, have invented certain new and useful Improvements in Typewriting Machines, of which the following is a specification.

My invention relates to manifolding 10 mechanism for typewriting machines, the purpose thereof being to provide manifolding devices in which a copy of all the letters or other matter impressed upon successive work-sheets may be made upon a continuous web of paper carried by the carriage of the machine; and for facilitating the making of an additional carbon copy upon a separate sheet introduced into the machine along with each work-sheet, as distinguished 20 from a continuous web.

My invention includes a frame on the carriage which serves as a support for the web of paper upon which a carbon copy of all the matter typed upon the work-sheet is 25 preserved, the said web extending about the platen together with an endless band or belt of carbon coated paper or fabric which also passes about the platen and a suitable guide roll carried by the frame, and which carbon 30 band travels in contact with the web referred to and produces a copy thereupon of the matter typed upon the work-sheet.

As an additional feature, a second endless traveling band or belt of carbon is provided, 35 which also passes about the platen of the machine and about guide rollers carried by the frame referred to; the second band resting upon and moving with the first-mentioned band and being so arranged that a 40 separate sheet of paper may be introduced between the two bands and a carbon copy made thereon by the second band or belt.

The work-sheet itself is inserted into the machine about the platen and outside the 45 second of the above-mentioned traveling belts or webs of carbon coated fabric, so that as the work-sheet is written upon a carbon copy is made upon the separate sheet of paper moving between the two traveling 50 carbon coated webs or belts, which sheet is removed from the machine along with the work-sheet; while a continuous record of all the matter typed upon successive work-sheets is preserved upon the endless web carried 55 by the frame and associated with the car-

riage of the machine until the web has been exhausted, this copy being produced by the inner one of the two traveling carbon coated belts referred to.

Other features and advantages will here- 60 inafter appear.

In the accompanying drawings,

Figure 1 is a view illustrating a type- 65 writer carriage equipped with my invention, the view showing an elevation of the device as seen from a position in front of the machine.

Figure 2 is a view principally in elevation 70 and showing the device as seen from a position to the left of Figure 1, or from the left-hand end of the typewriter carriage.

Figure 3 is a fragmentary view illustrating a detail of the platen.

Referring to the drawings, the reference 75 numeral 3 designates the traveling platen of a typewriting machine, the same being turned or advanced in a series of step-by-step movements by means of suitable feeding mechanism operating upon and through a ratchet wheel 4 operatively connected with the platen; 80 the details of the ratchet mechanism, however, not being illustrated or referred to herein as the same form no part of this present invention.

The two ends of the platen are supported 85 by the vertically movable shift frame having ends 5, 6 in the embodiment of my invention illustrated, to which frame ends the frame which carries the carbon bands and the endless web herein referred to is shown as secured.

The frame above referred to is illustrated 90 as carrying upright end members 7, 8, said uprights being preferably secured to one another and braced by a tie-bar 9 extending 95 between them to thereby impart rigidity to the frame as a whole. The Y form of the end members of the frame is illustrated in Figure 2 of the drawings; and said members are provided with bearings adjacent their 100 upper ends in which a shaft 10 carrying a guide roll 11 is journaled. The reference numeral 12 designates an endless band or belt of carbon coated paper or fabric extending about the guide roller 11 and about 105 the platen 3 of the machine.

The end members 7, 8 are provided each 110 with a slot 13, see Figure 2, and the reference numeral 14 designates a winding shaft, the ends of which are supported in

guide blocks located within the said slots, which shaft serves as a support for a winding roll of paper 15; the said roll constituting one end of a web of paper 16 upon 5 which a continuous record of the writing impressed upon successive work-sheets is preserved, which strip or web passes about the platen 3 between the same and the carbon band 12. The other end of said web or 10 strip is wound upon or formed into a supply roll 17, the latter roll being supported by a shaft 18 the ends of which are also supported in guide blocks located within the slots 13 formed in the frame members. 15 Interposed between the rolls 15 and 17 is an idle roller 19, the same being carried by a shaft 20 the ends of which are also supported in guide blocks located within the slots 13. Springs 21 acting against abutments 22 carried by the end frames, and which springs act upon the shaft 18 through the guide blocks whereby its ends are supported, are also provided, the purpose of these springs being to force the upper paper 25 roll 17 downward and thus keep the web surfaces of the rolls 17, 15 in firm contact with the intermediate idle roller 19.

In view of the premises it will be appreciated that as the platen 3 is advanced, ordinarily in the direction of the arrow shown 30 in Figure 2, the rear reach 23 of the continuous web of paper 16 will be subjected to tension, and the strip of paper will be withdrawn or unwound from the upper roll 35 17. The rotary motion of the surface of this roll of web 17 will be transmitted through the idle roller 19 to the surface of the lower roll of web 15, the rotation of which last-mentioned roll will wind the 40 front reach 24 of the web thereupon; the web being wound upon this last-mentioned roll with the same speed that it is unwound from the first-mentioned rolls as the rate of movement of the peripheries of the rolls 17 45 and 15 is equal at all times, as will be appreciated. The web of paper upon which the continuous record is made is therefore unwound from one of the rolls and simultaneously wound upon the other by the action of the platen of the machine, transmitted through the strip itself, and no auxiliary means is necessary to advance the strip.

In a device such as is above described it 55 is obvious that successive work-sheets may be inserted into the machine and typed upon, and that a continuous record of all the matter typed upon a plurality of such sheets will be preserved upon the web 16 carried by 60 the rolls 15 and 17. My invention in its more comprehensive form, however, includes means whereby a carbon copy of the matter written upon a work-sheet may be made upon a separate sheet to be inserted into the 65 machine along with the work-sheet, and re-

moved therefrom at the completion of each individual work-sheet, without, however, interfering with the continuous record preserved upon the web carried by the rolls.

In order to accomplish the end last above 70 referred to I provide the end frames 7, 8 with additional pairs of bearings upon the branches of the Y's within which shafts 25, 26 carrying idle rollers 27, 28 are journaled; and 29 designates a second endless band or 75 web of carbon coated paper or fabric which passes around said last-mentioned idle rollers and about the platen of the machine, said second belt resting upon and moving with the first-mentioned belt 12. The bearings for the shafts 25, 26 are preferably spaced apart from one another in order to maintain the stretches of the belt or band 29 extending from the platen sufficiently spaced 80 from the corresponding stretches of the band 12, so as to facilitate the introduction between the two carbon bands 12 and 29 of a sheet 30, which sheet in introducing it into the machine may if of considerable length be doubled loosely upon itself, as shown in 85 dotted lines in Figure 2.

The sheet 30 is provided for the purpose of making a carbon copy of the matter written on the work-sheet 31 with which the type carried by the type-bars 32 engage, the usual vibrating ribbon mechanism 33 being provided in order to secure an impression of the type upon the outer or original work-sheet 31. A carbon copy of the matter typed upon each sheet 31 is obviously produced upon a second sheet 30 by means of the outer traveling band or belt 29, while a second carbon copy of the matter typed upon a plurality of work-sheets is impressed upon the continuous web 16 by 100 means of the inner carbon band or belt 12; thus providing a separate carbon copy of each successive letter typed, and also preserving a copy of all the matter typed upon successive work-sheets upon the web carried 105 with the rolls 15, 17, permanently associated with the carriage.

In order to facilitate the setting up of the manifolding device as a whole the platen 3 is preferably made easily removable from the end plates 5, 6 whereby it is carried, for which purpose the said end plates, as shown in Figure 3, are provided with short shafts 34, the inner ends of which are provided with square recesses into which a fixed support or trunnion 35 at one end of the platen, and a movable support or trunnion 36 at the other end thereof, enter, the last-mentioned or movable support being in turn carried by a bushing 37 inserted in an opening formed in the ends of the platen and the same being forced outwardly by means of a spring 38. A disk 39 fast upon the movable support 36 forms a finger-piece whereby the support 36 may be easily moved inward against the 110 115 120 125 130

action of the spring 38, to thereby free the platen from the short shafts 34. This permits the carbon bands 12 and 29 and the web upon which the continuous record is made to be properly placed within the supporting frame whereby they are carried, after which the platen is put in place with the supports 35, 36 in driving engagement with the shafts 34 carried by the end plates, as will be appreciated.

Variations may be resorted to within the scope of the invention, and portions of the improvements may be used without others.

Having thus described my invention, I claim:

1. In a device of the class described, the combination with a movable carriage having a revoluble platen mounted therein, of a frame mounted on said carriage, means on the frame for supporting a web extending about said platen and the ends of which are formed into a supply-roll and a winding roll, and means driven by the web-surface of the supply-roll and adapted to drive the winding roll by its web-surface to enable the drawing on the web to rotate the winding roll.

2. In a device of the class described, the combination with a movable carriage having a revoluble platen mounted therein, of a frame mounted on said carriage, means on the frame for supporting a web extending about said platen and the ends of which are formed into two rolls, and an idle roller interposed between said rolls and in contact with the web-surface of each of them and through which motion is transmitted from one of said rolls to the other.

3. In a device of the class described, the combination with a movable carriage having a revoluble platen mounted therein, of a frame mounted on said carriage, two rolls supported by the frame and carrying the ends of a web extending about said platen, so that there is a winding roll and a supply-roll, an idle roller interposed between said rolls and in contact with the outer web-surface of each of them whereby motion is transmitted from the supply-roll to the winding roll, and spring mechanism carried by said frame and adapted to force said rolls into engagement with the idle roller.

4. In a device of the character described, the combination with a revoluble platen, of means for supporting in distended condition above the platen an endless carbon-belt passing around the platen to be fed thereby, the carbon-belt being so supported as to extend from the platen in such directions that a work-web may be fed between the belt and the platen from the receiving side to the delivery side of the latter, and means for supporting in distended condition a longer endless carbon-belt passing around the platen outside of the first-mentioned belt

and extending from the platen in such directions that a work-sheet, to receive a carbon copy, may be inserted between the belts at the receiving side of the platen and delivered from the control of said belts at the delivery side of the platen.

5. In a device of the class described, the combination with a rotatable platen; of a frame; a shaft for a supply-roll of web journalled in the frame; a shaft for winding a roll of web after it passes the platen and likewise journalled in the frame; means for drawing on the web to draw it from the supply roll; an idler roller running upon the web surfaces of the supply and winding rolls to cause the drawing on the web of the supply roll to wind it upon the winding roll; and means for guiding a carbon web between the first-named web and an outer work-sheet.

6. In a device of the character described, the combination with a revoluble platen, of a frame in which the platen is journalled, a secondary frame extending upwardly from the first-mentioned frame and comprising Y-shaped end members, a roll journalled at the base of the fork in each of said Y-shaped members to hold in distended condition a continuous carbon-belt extending around the platen to be fed thereby, and two rolls, one mounted in the forward arms of said Y-shaped members, and the other in the rearward arms thereof, for holding in distended condition a longer continuous carbon-belt extending around the platen to be fed thereby and lying outside of the first-mentioned carbon-belt, the two rolls mounted in said arms serving to maintain the stretches of the second carbon-belt extending from the platen separated to such an extent from those of the first that work-sheets, to receive carbon copies, may be inserted between the belts at the receiving side of the platen, and be withdrawn therefrom at the delivery side of the platen.

7. In a device of the character described, the combination with a revoluble platen, of a frame in which the platen is releasably mounted, a secondary frame extending upwardly from the first-mentioned frame and comprising end members, web-controlling means mounted in said secondary frame and adapted to deliver a work-web to the platen when the latter is actuated and to take up the web from the delivery side of the platen, a roll mounted in said end members beyond the web-controlling means to hold in distended condition around the web-controlling means a continuous carbon-belt extending around the platen to be fed thereby, said roll being of sufficient size to cause the stretches of the carbon-belt extending from the platen thereto to be spaced far enough apart to receive the web-controlling means without contacting therewith, and two rolls

mounted in said end members above the first-mentioned roll for holding in distended condition a longer continuous carbon-belt extending from the outside of the first carbon-belt around the platen to be fed thereby, the two rolls cooperating with the longer carbon-belt being so positioned with reference to the roll which guides the first-mentioned carbon-belt as to hold the second carbon-belt away from the first carbon-belt at the receiving and delivery sides of the platen to enable a work-web, to receive a carbon copy, to be fed between the belts at the receiving side of the platen and to be freed therefrom at the delivery side of the platen.

8. In a device of the class described, the combination with a movable carriage hav-

ing a revoluble platen, of a frame mounted on said carriage and comprising an upwardly-extending member, a supply-roll shaft and a winding-roll shaft journaled in said member, and an idler roller journaled in said member between said shafts and adapted to bear on the web-surfaces of a web wound on both of the rolls to cause drawing on the supply-roll by the platen to turn the winding roll, said rolls and roller being out of contact with the platen and having their longitudinal axes in the same plane.

EDWIN MARC FRANCOIS GUIGNARD.
